UNITED STATES PATENT OFFICE.

PHILIP KEMPTER, OF MILWAUKEE, WISCONSIN, ASSIGNOR TO GEUDER, PAESCHKE & FREY CO., OF MILWAUKEE, WISCONSIN, A CORPORATION OF WISCONSIN.

SHEET-METAL MACHINE-FRAME CONSTRUCTION.

1,210,174.

Specification of Letters Patent. Patented Dec. 26, 1916.

Application filed June 30, 1916. Serial No. 106,784.

To all whom it may concern:

Be it known that I, PHILIP KEMPTER, a citizen of the United States, residing in Milwaukee, county of Milwaukee, and State of Wisconsin, have invented certain new and useful Improvements in Sheet-Metal Machine-Frame Construction, of which the following is a specification.

This invention relates to the construction 10 of machine frame or casing members which carry shafting, gearing or other machine elements which are required to be maintained in precise position or alinement, the frame or casing being made wholly or chiefly from 15 sheet metal.

The use of bent, stamped or drawn sheet metal for various structural purposes has been greatly extended in recent years, as the processes for manipulating such metal and 20 producing desired shapes have been perfected, and it is now recognized that, wherever its use is possible, it possesses marked advantages over cast metal as a structural material. Generally speaking, these advantages are that it has a high tensile strength 25 and so is stronger and lighter. It may also be formed thinner than is practical with cast metal, further insuring lightness, and it may be worked cheaper than cast metal, 30 particularly where articles are to be made in considerable quantities. Its use has, however, not been considered practicable for many purposes because of the inability to machine it so as to produce accurately fitted surfaces and because of its lack of 35 rigidity. For the latter reason its use has been deemed impractical where it would be required to support machine elements transmitting substantial power, as for instance, 40 engine crank shafts, transmission shafts, heavy gearing, etc. In such cases no way has been known of securing the high degree of rigidity necessary to enable the frame or casing to withstand the re-actions caused by 45 the power transmission without yielding to such an extent as to destroy the alinement of the bearings or gearing and so preventing satisfactory operation. For these reasons, cast metal exclusively has been retained in 50 use as the structural material for supporting such machine elements. As an example of this situation modern automobile construction may be referred to. In automobile construction lightness is a most important desideratum, and furthermore due

to the large scale production which now obtains, great numbers of identical parts are manufactured. Sheet metal has accordingly been adopted as the structural material, wherever it has been thought possible to use 60 it, as, for instance, for fender and body parts and also lower half crank case members which are not required to withstand high stresses due to the operation of the engine. Other parts of the construction have, however, continued to be made of cast metal, such for instance as the engine cylinders, the upper half crank case member, which carry the bearings for the engine, crank shaft and cam shaft, and the transmission 65 casings or gear boxes which carry the transmission gearing and countershafts. In the more expensive cars these parts have frequently been made of cast aluminum, so as to reduce the weight as far as possible, 70 but the cost of this material has been prohibitive of its use in the cheaper cars, and cast iron has therefore been generally used with corresponding very substantial increase in weight. 75

My present invention relates to the construction of bearing and shaft supporting parts and the like mainly or wholly from sheet metal, but reinforced in such a way as to secure the necessary rigidity and strength, 80 whereby I am enabled to manufacture these parts as light as or lighter than if made of cast aluminum, and at a cost less than that of cast iron parts. 85

In the accompanying drawings which 90 form a part of this specification, I have shown certain preferred embodiments of my invention as illustrative of the principle thereof and of the best mode now known to me for practising the same. For such illustrative purposes I have chosen a unit power plant construction for automobiles which embodies two forms of casing or supporting members of novel construction, a gear box or transmission casing and an upper half 100 crank case member, but it will be understood that my invention is applicable to other uses.

In the drawings, Figure 1 is a side view, partly in section, of a unit power plant for 105 automobiles. Fig. 2 is a perspective view of the gear box or transmission casing shown in Fig. 1. Fig. 3 is a longitudinal sectional view of one end of the gear box, reinforcing plate and bearing member, the position of 110

the section being indicated by line III—III on Fig. 2. Fig. 4 is a bottom plan view of the upper half crank case member of the power plate shown in Fig. 1. Fig. 5 is a 5 transverse section on line V—V of Fig. 4. Figs. 6 and 7 are perspective views of the opposite sides of a crank case, having an upper half crank case member of the form shown in Fig. 4. Fig. 8 is a perspective 10 view of the lower half crank case member.

Referring to the drawings in detail, Fig. 1 shows a unit power plant construction, such as is employed in automobiles and comprises the engine 1 and the sliding gear 15 transmission 2. Unit power plant construction is characterized by the fact that the transmission casing or gear box is rigidly connected with the engine crank case, the main transmission shaft being thereby 20 maintained in permanent fixed alinement with the engine crank shaft. The chief parts of the engine are the cylinders 3, the upper half crank case 4 and the lower half crank case 5. These two members form the 25 casing and inclose the crank shaft 6 to the cranks of which the connecting rods 7 are attached. At the upper ends the rods engage the pistons (not shown). The engine will, of course, be provided with suitable 30 valve mechanism, which it has not been thought necessary to illustrate, the valves being operated from the cam shaft 8, which is driven from the crank shaft through suitable gearing 9. At the opposite end the 35 crank shaft carries the fly wheel 10 with which engages the clutch cone 11, which is mounted on the transmission shaft 12. The transmission gears 13 are mounted on this shaft and on the countershafts, one of which 40 is illustrated at 14. These operative parts of the engine and transmission have been illustrated conventionally as they form no part of my present invention. The latter relates to the construction of supporting 45 members or casings for the operative parts, these casings being made of sheet metal, and so constructed and reinforced as to be capable of sustaining the shafting, gears, etc., in proper operative alinement. I will 50 now describe the construction of these novel supporting or casing members, referring specifically first to the transmission gear box shown in Figs. 1, 2 and 3. 20 indicates the gear box or transmission casing, which 55 may be either formed integrally from a sheet metal drawing or may be built up of sheet metal elements united by autogenous welding or otherwise. Where the casing forms part of a unit power plant construc- 60 tion as in the example illustrated, it will preferably have a fly wheel housing section 21, also preferably made of sheet metal and united to the casing by welding or otherwise, this housing having a flange 22 by which it 65 may be bolted to a flange on the crank case.

The gear casing is preferably open at the top as shown at 23 and may also be provided with other openings such as 24 in the side walls. Suitable openings, such as 25, 26 and 27 are formed in the end walls of the 70 casing for the bearings for the shafts upon which the gears are mounted. In order to reinforce the casing and more particularly to provide the necessary stock to permit the 75 surfaces to be machined so as to make accurate fitting and alinement of the parts possible, reinforcing plates of relatively heavy rolled or other metal are attached at proper locations in any suitable manner, as by spot welding. In the construction illustrated, reinforcing plates 28 and 29 are welded to the end walls of the casing and the outer surfaces thereof are accurately machined, so as to form proper supporting 80 surfaces for the members 30 which carry the bearings 31 for the shafts. The bearing carrying plates or members 30 are preferably formed of cast metal and may, of course, be provided with bearings of any suitable character, those illustrated being ball bearings. These plates have accurately machined inner surfaces adapted to fit the machined surfaces of the reinforcing plates 28 and 29 and to be secured in place thereon in any suitable manner as by cap screws 32. 85 The plates 28 and 29 provide sufficient stock for the proper engagement of these screws or other attaching means. The flange 22 is also preferably provided with a reinforcing plate 33 which may be machined so as to insure the proper alinement of the gear box and the engine crank case when the two are bolted together, this plate also strengthening the flange and providing adequate stock for engagement of the attaching bolts. 90 The openings 23 and 24 in the gear box are also preferably provided with reinforcing plates 34 and 35 about their peripheries, which may be machined to permit the lids or covers for these openings to be fitted 95 tightly thereto, so as to prevent the escape of grease or entrance of dust or dirt, and to provide stock for the engagement of the cover attaching screws. The surfaces of the 100 plates 28 and 29 and of the bearing carrying frames or plates 30 being machined true, it will be seen that the bearings may be alined with the necessary accuracy, and, owing to the reinforcement of the sheet 105 metal casing by these plates, such alinement will be accurately maintained notwithstanding the heavy stresses resulting from the transmission of power through the gearing. In this way, it will be seen that a casing formed chiefly of sheet metal is provided which is cheap to construct, light and at the same time strong and rigid, so as to be able to support the power transmission 110 gearing and shafts mounted therein.

Referring now to the crank case which is 115

illustrated in detail in Figs. 5 to 8 inclusive, this is constructed in parts as is customary in this type of engine, the engine crank shaft being mounted in bearings located at 5 the plane of separation between the two crank case members, while the engine cylinders are bolted to the upper half crank case member in a well-understood manner. The lower half crank case member 5 is of 10 any suitable construction, it being shown as comprising a sheet metal stamping or drawing having within the same an oil reservoir or pan 40. Around its upper edge it is preferably reinforced by a welded-on plate 41, 15 which may be machined to a true surface, so as to fit closely against the bottom flange of the upper half crank case member. The upper half crank case member 4 comprises a sheet metal stamping or drawing 42 which 20 forms its main shell. This shell has at its lower edge a projecting flange 43 preferably reinforced by a welded-on plate 44, the lower half crank case member being bolted or otherwise suitably connected to this flange. On 25 top of the shell is a plate 45 also preferably welded on, which is machined true, so as to form a base for the engine cylinders which are adapted to be firmly secured thereon in any suitable manner, preferably by bolts 46. 30 (See Fig. 1.) In order to strengthen and render rigid the shell 42 and more particularly to provide rigid means for supporting the engine crank shaft and cam shaft, I secure in the shell a suitable number of bearing 35 supporting members or brackets 47, which are rigidly constructed, preferably of cast metal. These bearing supports or brackets are secured in the shell in any suitable manner as by welding, riveting or bolt- 40 ing. The number of these brackets used corresponds to the number of bearings on the crank shaft, and as illustrated each bracket has a bearing recess 48 in its under side, the bearings being completed by caps 45 49 held in place by bolts 50 or otherwise. The brackets are also provided with suitable recesses 51 to receive the cam shaft bearings 52. (See Fig. 1.) The cylinder castings being secured directly on the top plate 50 of the upper half crank case shell, and the brackets 47 carrying the crank shaft, being rigidly secured within the shell and abutting directly against the under side of the top thereof, it will be seen that accuracy of 55 alinement and rigidity of relation between the cylinders and crank shaft will be assured and satisfactory operation of the engine thereby achieved. In some cases, in fact, the bolts 50 may be extended at their 60 upper ends through the flanges in the lower ends of the cylinders or into the cylinder castings so as to directly connect the cylinders and brackets. Accuracy of alinement of the cam shaft is also secured by reason 65 of its being mounted in the brackets. At the

same time, the shell constituting the chief part of the upper crank case member is made of sheet metal of great thinness but high tensile strength so that a large saving in weight is obtained over crank cases made 70 of cast iron. The shell moreover is of such shape and construction that it can be stamped or drawn between dies in a very simple manner and at a very low cost, it being easier to make a thin shell of this 75 character by such process than by casting. The cast bearing supporting brackets are moreover of such a character that the casting operations are very simple so that all the parts of the crank case can be manufactured at a minimum cost. 80

The crank case may be provided, if desired, with suitable supplemental parts or casings for inclosing the timing gears, fly wheel, etc. As illustrated, a sheet metal 85 casing 60 is provided at one end of the crank case in which the timing gears and generator driving gear are adapted to be mounted, while, at the other end the crank case is provided with a flanged housing 61 for the 90 fly wheel. The flange 62 of this housing is adapted to have bolted to it the flange 22 of the complemental housing member 21 of the transmission gear box, in the particular construction shown. In the construction of 95 crank case illustrated, I have shown the flange 43 of the upper half crank case member extended at one side to form a shelf 65 which is adapted to support the electrical units, such as the generator 66 (indicated in 100 dotted lines in Fig. 7), or other auxiliaries, the shelf being preferably strengthened by welded-on brackets 67. A very firm, and at the same time, cheap and simple support for these auxiliaries is thus provided. 105

From the foregoing it will be seen that I have devised a sheet metal construction for the casings or supporting members of machine elements, in which the advantages of both sheet metal and cast metal construction 110 are obtained. While the structures are chiefly formed of sheet metal, with its attendant advantages, these sheet metal parts are reinforced at the needed points. Extra stock is provided where required to add 115 strength or to provide for machining and the actual support and alinement of the bearings is accomplished by the use of rigid portions, preferably formed of cast metal.

It will be understood that my invention is 120 not limited to the particular construction above described but that the principle of my invention may be applied in other ways and for other purposes.

Having thus described my invention, 1-125 claim:

1. In a support for shafting and the like, the combination of a sheet metal casing and cast metal bearing carrying members attached thereto and supported thereby. 130

2. In a sheet metal housing for machine elements, such as shafting, gearing, etc., the combination of a sheet metal casing and rigid bearing supporting frames rigidly attached thereto and supported thereby.
3. The combination with a sheet metal housing for machine elements, including a plurality of rotatable shaft members, of rigid frames secured to said housing and supported thereby, and bearings for a plurality of said rotatable members carried by said frames, said bearings being located in predetermined rigid relation to each other.
4. A sheet metal housing of the character described, reinforcing plates rigidly secured thereto, the surfaces of said plates being machined to predetermined dimensions, and cast metal bearing supporting frames rigidly attached to said housing.
5. In automobile construction, the combination of an engine crank case including an upper half crank case member of sheet metal and the sheet metal gear box attached to said crank case.
6. In automobile construction, the combination of an engine crank case including a sheet metal upper half crank case member, said crank case having a flanged fly wheel housing at one end thereof, and a sheet metal transmission gear box having an extension carrying a flange secured to the flange of said fly wheel housing on the crank case.
7. A sheet metal transmission gear box, cast iron frames secured thereto and supported thereby, and bearings carried by said frames for each of the shafts in said gear box, whereby said shafts are held in predetermined relative alinement.
8. A sheet metal transmission gear box reinforcing plates rigidly secured to the ends thereof, the outer surfaces of said plates being machined true, and cast iron bearing supporting frames attached to said plates.
9. A sheet metal transmission gear box having a flanged extension at one end thereof for attachment to a crank case and having reinforced ends, and bearing frames carried by said ends.
10. In engine construction, a sheet metal upper half crank case member, and rigid bearing carrying members rigidly mounted therein and supported thereby.
11. In engine construction, a sheet metal upper half crank case member and cast metal bearing frames rigidly mounted therein and supported thereby.
12. In engine construction, a sheet metal upper half crank case member and cast metal bearing frames mounted therein and supported thereby, and bearings for the mainshaft and cam shaft of the engine provided in said frames.
13. In engine construction, a sheet metal upper half crank case member having a reinforced flange around its lower edge and a reinforced top member to which the engine cylinders are adapted to be attached.
14. In engine construction, a sheet metal crank case member having a flange around its lower edge, said flange being extended at one side to form a supporting shelf.
15. In engine construction, a sheet metal crank case member having a flange around its lower edge, said flange being extended at one side to form a supporting shelf, and brackets rigidly secured thereto for strengthening said shelf.
16. In engine construction, a sheet metal upper half crank case member and a cylinder supporting plate rigidly secured to the upper part thereof.
17. In engine construction, an upper half crank case member, comprising a drawn or stamped sheet metal shell, and cast metal bearing supporting brackets supported by the member and rigidly mounted therein transversely of said shell and suitably spaced.

PHILIP KEMPTER.
